Application February 3, 1947, Serial No. 726,142

7 Claims. (Cl. 164—112)

1

This invention relates to key operated machines for marginally slotting cards having sorting holes disposed adjacent their edges.

Cards or checks of the near marginally punched type are provided with a series of holes or perforations along their marginal zones, which may be grouped into fields arranged longitudinally of the card edge, with each field representing a single digit. The card is punched or slotted out to the card edge from one or more particular perforations in each field identifying a number, the progressive slotted arrangement from field to field indicating a grouping of numbers.

Certain types of cards of the foregoing character may include a plurality of parallel rows of holes arranged parallel to the card margin. As an example, in one type of card, each field includes four perforations, numbered 1, 2, 4 and 7, the first three numbers being arranged in alignment parallel to the card edge, and the fourth number being spaced inwardly of the 4 perforation and in alignment therewith on a line perpendicular to the card edge. To indicate numbers 1, 2 or 4, the card is slotted from its edge inwardly to the perforation representing the desired number. To indicate the number 7, the card is slotted more deeply from the marginal edge, through the number 4 perforation, to the number 7 perforation. Numbers 3, 5, 6, 8 and 9 are obtained by slotting the card from its edge to the perforations representing a combination of two of the aforementioned numbers, which add up to the particular number desired. For example, 3 on the card edge in a selected field is indicated by slotting out to perforations 1 and 2; 8 on the card in a selected field is slotted out from the card edge to perforations 1 and 7, and so forth. To indicate 0, slotting or notching is not effected at all, the fact that the particular field is not slotted representing 0.

Following the slotting indicative of a particular number in one field, the card is slotted in the next adjacent field, and the slotting operation continued until the entire card has been appropriately punched to designate the desired number grouping.

It is an object of the present invention to provide an improved machine for allowing the opposite longitudinal marginal areas of the card of the character above referred to to be selectively, rapidly and accurately slotted through all of the fields along the selected card margin.

A further object of the invention is to provide a key operated card punching machine of the general character referred to which is compara-

2

tively simple in its construction and which may be operated efficiently in a rapid manner.

Another object of the invention is to provide an improved machine for preselecting one or more punches for slotting the marginal areas of a card prior to the actual slotting operation.

One form which the invention may assume is exemplified in the following description and illustrated by way of example in the accompanying drawings, in which:

Fig. 1 is a top plan view of a machine embodying the invention, parts being broken away to disclose the interior mechanism.

Fig. 2 is a perspective view, somewhat diagrammatic in character, disclosing the key operated mechanism for selecting the appropriate punch and for actuating the selected punch, and also the selector mechanism for determining the longitudinal margin along the card to be punched.

Fig. 3 is a perspective view, somewhat diagrammatic in form, showing the mechanism for shifting the cutters or punches progressively along the card or check from one perforated field to the next field.

Fig. 4 is a transverse section through the machine showing part of the operating mechanism.

Fig. 5 is a longitudinal section through the machine illustrating the carriage and escapement mechanism, and also the card holding portion of the machine.

Fig. 6 is an exploded view, showing the operative relation between the punches and the selector wheels.

Fig. 7 is a side elevation disclosing the relationship between the various selector wheels of a set with respect to one another.

Fig. 8 is a plan view of a portion of the marginal edge of a card to be punched.

Fig. 9 is a side elevation of the selector mechanism for determining which of the two longitudinal margins of the card is to be slotted.

Fig. 10 is a cross-section taken along the line 10—10 on Fig. 9.

Fig. 11 is a side elevation of part of the mechanism for actuating the punches.

Fig. 12 is a partial section taken along the line 12—12 of Fig. 1.

As disclosed in the accompanying drawings, a card slotting or notching machine is provided for operation on cards of the type commonly known in the industry as "Keysort" cards. As specifically illustrated in the drawings, and particularly in Fig. 8, one type of card 10 to be notched has its marginal portions divided into a plurality of longitudinally arranged fields 11,

each field having a plurality of rows of perforations, identified as 1, 2, 4 and 7. The perforations identified by 1, 2 and 4 are arranged at equally spaced distances apart in a row disposed longitudinally inwardly of and parallel to the card edge, while the perforation identified by 7 is spaced inwardly from the number 4 perforation in alignment therewith in a direction perpendicular to the card edge.

The fields 11 of a card of this type are arranged along both longitudinal marginal portions of the card, as well as along the side portions, each field being identical and adapted to indicate various identifying numbers. For example, the field beginning at the right end of a longitudinal card margin may indicate a unit, and each succeeding field to the left thereof indicates tens, hundreds, thousands, ten thousands, hundred thousands, etc.

In this description, and by way of example in describing the machine, it will be assumed that the number 25921 is to be punched along the top longitudinal margin of the card. Accordingly, one field will be notched or slotted in from the card edge to the number 2 perforation; the next adjacent field will be notched inwardly to both the 4 and 1 perforations, which add to provide the number 5; the next succeeding field will be punched into the 7 and 2 perforations, to provide the number 9; the next field will be punched inwardly to the number 2 perforation; and the last field will be punched inwardly to the number 1 perforation. Punching could be continued along the card edge for additional numbers whenever required, to the full capacity of the card.

The machine includes a frame comprising an outer housing 12 and vertically disposed stationary walls or standards, 13, 14, 15. A card holder or table 16 is supported on the upper ends of the end and intermediate walls 13, 14, being of a narrower width than the card 10 to be punched, and having its forward and rearward longitudinal edges 16a, 16b disposed adjacent corresponding sets of punch levers 18, 17 carried on a single punching head 19 slideable longitudinally of the holder or table 16 on guide bars 20, 21 secured to the end and intermediate vertical frame walls 13, 14. The punching head has a handle 22 disposed over the card holder table for enabling manual shifting of the head along the table 16 and card 10.

A card is placed on the holder table 16 and is appropriately positioned and held by mechanism now to be described. A lever handle 23 is pivotally mounted on the table and is engaged by a leaf spring 24 tending to hold its forward foot 25 in a downward position against the left side margins of the card. The lower arm 26 of the lever is provided with a notch 27 engageable with a pin 28 on a slide rod 29 extending under the table 16, the other end of the rod having a knob 30 projecting upwardly and adapted to engage a spring holder 31, whose outer end is secured to the table and whose inner end 31a is curved and adapted to bear against the right side of the card to hold it in place. The rod 29 and knob 30 are designed to elevate the spring holder 31 from the card to permit its removal and the insertion of a new card against a stop 32 on the table 16.

The lever handle 23 is elevated to remove its pressure foot 25 from the card 10 and to shift the operating rod 29 to the right, by means of the pin and slot connection 27, 28. Such shifting forces the knob 30 against the underside of the spring 31 and elevates it, permitting removal of

the card. Another card is then inserted in place and the lever handle 23 released, which causes its spring 24 to engage the foot 25 with the left margin of the card and the pin and slot connection 27, 28 to shift the knob 30 to the left, allowing the spring 31 to engage the right margin of the card. The card is appropriately positioned in view of the engagement of its right margin with the table stop 32.

The punching head 19 has a set of female die slots 33 (see Fig. 12) on each of its sides adapted to cooperate with the sets of cutter blades 17, 18 pivotally mounted in the head. Inasmuch as the sets of punches and dies 17, 17a and 18, 18a are identical, although oppositely disposed, a description of one will suffice for both. The inward edge 17b of a female die 17a is adjacent a side edge 16b of the table, the card margin resting on the horizontal die surface 17c from which the spaced vertical die slots 33 depend. There are three die slots corresponding in number to the notches capable of being made in each card field, and these slots are spaced apart from center to center a distance equal to the pitch between holes along the card margins. Cutter blades or punches 17, corresponding in number to the slots 33, are carried by the head 19 in vertical alignment with the slots 33, their inner punch portions 34, 35, 36 being movable between vertically spaced plates 37 into and out of the die slots 33. The punches are mounted for pivotal movement on a common fulcrum pin 38 extending therethrough and through the outer end of the head, being urged out of the cooperable die slots 33 and against a common stop pin 39 by springs 40 engaging the outer operating arms 34a, 35a, 36a of the punch levers and encircling the fulcrum pin 38.

It is to be noted that the punch portions of the blades 17 do not all extend inwardly from the fulcrum pin 38 to the same extent. The punches 34, 35 for notching the edge of the card inwardly to the number 1 and 2 perforations are identical, whereas the punch 36 for notching the card inwardly to either the number 4 or 7 perforation is dissimilar, having a lower punch portion 36d for notching the card from its edge to the number 4 perforation, and an upper portion 36e extending inwardly to a greater extent than the lower portion for continuing the notching of the card from the number 4 perforation to the number 7 perforation. In notching into the number 1, 2 and 4 perforations, the cutter blades 17 are given the same extent of movement, whereas, in notching into the number 7 perforation, the blade punch 36 is given a greater extent of movement, as later described.

Each set of punches is operated in accordance with the selective settings of a plurality of indexing regulator wheels 41. These wheels are arranged in sets of three progressively along the machine, in order to cooperate with the three cutter blades as they are positioned progressively to notch a card 10 in each field 11. As indicated in the drawings, there are three indexing regulator wheels 42, 43, 44 for each field, and, since there are eleven fields provided for along each longitudinal edge of a card, there are a total of thirty-three regulator wheels. Since each set 41 of regulator wheels is a duplicate of the other, a description of one set will suffice for all.

Each indexing wheel in a set is provided with peripherally spaced prongs or projections adapted to engage an associated depending finger 75 34b, 35b, or 36b on a cutter blade. Each set

of regulator wheels has one wheel 42 with four prongs or projections 42a spaced therearound adapted to engage the punch 34 for notching the cards into the number 1 perforation. Similarly, the intermediate wheel 43 has four prongs or projections 43a adapted to engage the finger 35b on the intermediate cutter blade 35 for notching the card from its marginal edge to the number 2 hole. The other wheel 44 has a total of six prongs or projections, three 44a of which are adapted to engage the lever 36 to notch the card from its outer edge to the 4 perforation, and the other three 44b of which extend outwardly from the axis of the wheel to a greater extent than the number 4 projections 44a, in order to engage the finger 36b and impart a greater movement to the punch 36 and notch the card to the number 7 perforation. By variously rotating the wheels, their projections may be aligned with the punch fingers 34b, 35b, 36b to produce actuation of the punches singly or in groups of two, for the purpose of notching each card field 11 to the desired extent.

The punch head 19 is slidable along the guide bars 20, 21 in one direction, as to the right as viewed in Figs. 1 and 3, by a spring operated tape 45 wound on a spool 46 rotatable on a pair of brackets 47 suitably secured to the end supporting wall 15, with the inner end of the tape being suitably attached to the right end of the punch head carriage 19a. The carriage may be moved to the left against the action of the spring tape 45 by manual grasping and shifting of the handle 22 in the direction indicated.

The carriage 19a is movable step by step during the operation of the machine by the spring tape 45, as permitted by an escapement mechanism. Such escapement mechanism is of the general type described in Patent No. 2,041,085, and includes a rack 48 secured to the carriage and having teeth 49 on its underface spaced the same distance from each other as the distance from the beginning of one field 11 on the card 10 to the next field. The rack is held and stopped, to correspondingly control the punch head and its cutter blades in appropriate alignment with the field on the card, by a pawl mechanism, including a holding pawl 50 pivotally mounted upon a suitable rod 51 carried in the frame and having its nose 52 movable upwardly into engagement with the ratchet teeth 49 to prevent further movement of the ratchet 48 and the punch head 19 to the right. This pawl 50 has a pin 53 extending from its face into a slot 54 provided in a lever arm 55 fixed to a shaft 56 carrying a stop or escapement pawl 57 similar to the holding pawl 50 and movable upwardly into engagement with the rack teeth 49. By virtue of the interconnection between the pawls 50, 57, they move upwardly and downwardly in opposite directions, as will be explained later.

At the present time it may be pointed out that the pawls are rocked about their pivotal axes by the oscillations of an arm 58 secured to the shaft 56 and having motion transmitted to it by being pivotally attached to the upper end of a link 59 whose lower end is pivoted to an arm 60 secured on a rock shaft 61 suitably journalled in the frame of the machine and extending to a position adjacent the end supporting wall 15. Spaced operating arms 62 are secured to the shaft 61 between the intermediate and end walls 14, 15 extending rearwardly and having a rod 63 interconnecting their outer ends. The rod 63 extends under a plurality of key levers 64 piv-

otally mounted on a shaft 65 secured to and between the intermediate and end walls 14, 15 of the frame, the levers 64 extending forwardly of the machine where vertically arranged key stems 66 project upwardly from the frame for attachment to suitable keys 67 ranging from 0 to 9, constituting the operating keyboard of the key-punch mechanism.

The regulator wheels of each set 41 are secured to a selector shaft 68 rotatably mounted in a pair of spaced lever arms 69 oscillatable on a guide bar 20. The shaft 68 projects outwardly from the inner arm 69 and has a pinion 70 secured to it and adapted for engagement with the teeth 71 of a rack bar 72, selectively shiftable lengthwise in accordance with the depression of any selected key 67 on the keyboard. The rack bar is carried on a rocker carriage 73 pivotally mounted on a stud 74 secured to the intermediate wall 14 of the machine frame, being slidably guided through slots 75 defined by upper and lower spacer blocks 76 and outer plates 77 suitably attached to the carriage 73. A lock lever 78 is pivotally mounted on the carriage 73, having teeth 79 on its outer end engageable with the pinion 70 to lock it against movement when the index wheels 41 are all turned to a 0 position. This lock lever 78 is movable toward engagement with the pinion 70 by a spring 80 secured to a lever lug 81 and to a pin 82 projecting from the guide plate 77. Movement of the lever 78 toward the rack 72 under the influence of the spring 80 is limited by engagement of the lug 81 with the upper spacer block 76. It is to be noted that the rack bar 72 has both forward and rearward teeth 71a, 71 engageable with the forward and rearward index wheel pinions 70a, 70, and that there are two oppositely directed lock levers 78a, 78 engageable with the pinions.

By appropriately rocking the carriage 73, the rear rack teeth 71 may engage the pinion 70 with the co-operable rear lever 78 shifted upwardly from engagement with the pinion 70, while the forward rack teeth 71a are disengaged from the pinion 70a, and its lock lever 78a engaged with the pinion 70a. Such rocking occurs through the medium of a control lever 83 pivoted in the forward part of the machine to the left of the keys 67 and movable to a top position to rock the carriage 73 and move its rear end upwardly and its forward end downwardly. This movement is transmitted through a connecting rod or link 84, having one end pivoted to the lever 83 and its other end pivoted to a composite pressure lever 85 oscillatable on a shaft 86 secured to the intermediate and end walls 14, 15 of the frame. A pin 87 at the upper end of the pressure lever is rideable along a curved surface 88 on the underside of the carriage 73 extending on both sides of its pivotal axis 74, being maintained in snug engagement therewith by spring means. The pressure lever 85 is composed of several parts, including a supporting member 89 oscillatable on the shaft 86, an adjacent pin carrying member 90 slidably attached to the supporting member by a pin and slot connection 91, 92, and a tension spring 93 secured to the upper end of the supporting member 89 and lower pin 91, urging the member 90 upwardly and its pin 87 firmly against the curved carriage surface 88, which extends on opposite sides of the carriage fulcrum 74.

The selection of the rack teeth 71 or 71a and levers 78 or 78a engageable with the pinions 70, 70a is determined by shifting of the lever 83. Its movement to the topmost position engages the 75 rear rack teeth 71 with its associated pinion 70

and the forward lock lever 78a with its pinion 70a, at the same time disengaging the rear latch lever 78 from its pinion 70 and the forward rack teeth 71a from its pinion 70a. Conversely, movement of lever 83 to the bottom position engages the forward rack teeth 71a and rear lock lever 78 with their respective pinions and disengages the forward lock lever 78a and rear rack teeth 71 from their respective pinions.

Following the selection of the longitudinal card edge to be punched through manipulation of the lever 83, the rack bar 72 is slideable along the carriage 73 in mesh with a pinion to a predetermined extent, dependent upon the depression of a particular key 67 on the keyboard. Depression of a selected key effects rotation of the shaft 68 carrying the selector wheels 41, and positions their prongs 42a, 43a, 44a, 44b in alignment with the punch fingers 34a, 35b, 36b, or positions such prongs completely out of alignment with the fingers, allowing them to enter the space between the prongs. The prongs are so arranged as to provide the appropriate notching of the card from its marginal edge to the proper perforations.

Each key stem 66 is attached to a key lever 64 which has an intermediate cam face or nose 94 adapted to engage a rod 95 extending between a pair of follower levers 96 journaled on a pivot pin 97 secured to the frame of the machine. The inner follower lever 96 has a link 98 pivotally attached to it, whose other end is attached to a selector lever 99 pivotally mounted on the same rod 86 serving as the fulcrum for the pressure lever 85. This selector lever 99 has its upper end pivotally attached to a mid-point of the rack bar 72 by a suitable pin 100, and it is also provided with an intermediate triangular shaped opening 101 having downward converging tapered sides 102. A restoring mechanism cooperates with these tapered sides, to produce centering of the indexing wheels 41 to their 0 position. Such restoring mechanism consists of a curved lever 103 pivotally mounted on a bracket 104 secured to the base of the machine, whose bifurcated upper end 105 straddles the selector lever 99 and has a follower 106 extending into the opening 101. The follower 106 is urged against the tapered sides 102 defining the opening 101 by a suitable spring 107 attached to the lever 103 and to the base of the machine.

The key levers 64 associated with the keys 67 ranging from 1 to 9, inclusive, have different inclinations on their cam faces 94. Some of the cam face inclinations extend in the same direction, but vary in degree from one another, while other cam faces are inclined in the other direction, engaging the other side of the bar 95 connected to the follower levers 96. The faces are so chosen that the particular key depressed will rock the selector lever 99 and slide the rack bar 72 to the desired extent and in the proper direction, in order to rotate the pinion gear 70 engaged with the rack to the required extent, and thus appropriately align the prongs on the selector wheels 41 with the depending fingers of the cutter blades 17.

After depression of a key 67, to select and position the index wheels 41, the notching of the card takes place through the intermediary of a motor driven mechanism. The index wheels 41, as above noted, are secured to a shaft 68 rotatable within the spaced supporting levers 69 pivoted on the guide bar 20. The other, forward set 41a of regulator wheels is also mounted on a shaft 68a rotatable in spaced levers 69a oscillat-

able on the other guide bar 21, the two sets of levers 69, 69a being interconnected through a pin and slot device 108, 109 at their adjacent ends, in order that oscillation of one lever 69 imparts a corresponding oscillation to the other lever 69a.

Oscillation of the levers 69, 69a and upward and downward movement or translation of the indexing wheels 41, 41a occur as a result of the rotation of an electric motor 110, which revolves a crank 111, whose crank pin 112 is pivotally secured to the lower end of a connecting rod 113, whose upper end is attached to the outer end of an operating lever 114 through a ball and socket swivel connection 115. This lever 114 is attached to a rock shaft 116, suitably journaled in the frame of the machine, to which spaced arms 117 are secured. A pair of links 118 secure the outer ends of the arms 117 to the outer ends of the spaced levers 69 mounting the index wheel shaft 68. Rotation of the motor 110, through the crank 111, connecting rod 113, lever and link mechanism 114, 117, 118 described, elevates the supporting arms 69 for the indexing wheels 41 and causes the selected projections on the wheels 41 to engage selected cutter blade fingers 34b, 35b, 36b, swinging such fingers upwardly and the blade punches 34, 35, 36 downwardly to appropriately notch the card in the particular field 11 adjacent which the set of blades has been positioned.

The last portion of the movement of each key 67 being depressed causes the lower end of its stem 66 to engage a switch 119 and close the circuit to the electric motor 110. Such depressed key is held in its lower position by engagement of its detent nose 120 with the underside of a holding bar 121 extending across all of the key levers 64. This bar 121 extends substantially at right angles from a lever 122 pivotally mounted on the intermediate wall 14 of the machine, and having an arcuate upper lever arm 123 provided with a cam surface 124 adapted to be engaged by a pin 125 projected from the forward index shaft operating lever 69a. During upward movement of the shaft 68a, the pin 125 is ineffective to actuate the lever 122, a spring 126 attached to the detent bar 121 and to the frame of the machine urging the bar into holding position over the selected key lever detent 120. However, downward movement of the lever 69a and shaft 68a toward initial position causes the finger 125 to engage the lever cam surface 124, rocking the upper arm 123 rearwardly and the detent bar 121 forwardly, free from engagement with the key lever detent 120, and allowing a return spring 127, whose lower end is attached to the forward portion of the key lever 64 and whose upper end is attached to a pin 128 extending across the levers 64, to elevate the key lever to its uppermost position.

Depression of the number 1 key rocks the selector lever 99 to a certain extent and appropriately shifts the rack 72 to rotate the meshed pinion gear 70 and place a prong or projection 42a on the number 1 selector wheel 42 in its uppermost position in alignment with the number 1 punch finger 34b, causing the motor operated mechanism to operate the number 1 punch 34 only upon closing of the switch 119 by the key stem 66. Similarly, depression of the number 2, 4 or 7 key appropriately rotates the selector shaft 68 through the rack and pinion 71, 70, to cause a number 2, or number 4 or number 7 wheel projection 43a, 44a or 44b to be aligned with the number 2, 4 or 7 lever 35a or

36a, to accomplish appropriate notching of a card in a particular field. Depression of the number 3 key causes the regulator wheel shaft 68 to be rotated to such an extent that both a number 1 and a number 2 projection 42a and 43a are aligned with the number 1 and the number 2 punch 34, 35, in order that actuation of the motor operated mechanism elevates the index wheel shaft 68 and operates both punches to notch the card inwardly from its edge to the number 1 and 2 perforations.

Similarly, number 5 key depression rotates the selector shaft 68 and aligns a projection 42a on the number 1 wheel and a projection 44a on the number 4 wheel with the corresponding 1 and 4 punch lever 34a, 36a, to cause two corresponding notches to be punched in the marginal edge of the card. Depression of the number 6 key aligns both the number 2 and the number 4 projections 43a, 44a with the corresponding levers 35a, 36a; depression of the number 8 key aligns both the number 7 and the number 1 projections 44b, 42a on the selector wheels with the punch levers 36a, 34a; and depression of the number 9 key aligns both the number 7 and number 2 projections 44b, 43a on the selector wheels with the punch levers 36a, 35a. It is to be noted that in each instance alignment of the number 7 projection 44b, which extends radially outward a greater extent than the number 4 projection 44a, provides a deep notch in the card to the inward number 7 perforation.

Depression of the 0 key effects no movement of the rack bar 72 at all, which is normally urged into a position in which none of the projections on the wheels are in alignment with the cutter blade fingers 34b, 35b, 36b by the spring urged lever 103 and follower 106 acting on either inclined face 102 of the selector lever 99 and tending to center the rack bar 72 and selector shaft 68 to a 0 position.

Let it be assumed that the number referred to above, 25921, is to be notched on the upper longitudinal margin of the card 10. The punch head handle 22 is grasped and the head 19 is moved to the left of the machine, which places the cutter blades in alignment with the perforations in the first field 11 to be slotted. Since the upper marginal area is to be notched, the control lever 83 is shifted to its top position, which appropriately rocks the carriage 73 on its pivot 74 and engages the rear rack teeth 71 with the pinion 70 and removes its opposite latch 78 from engagement with the same pinion. Such rocking of the carriage disengages the forward rack teeth 71a from the pinion 70a and engages the forward lock lever 78a therewith to prevent inadvertent rotation of the forward selector wheels 41a from the 0 position. It is to be noted that the selector mechanism is normally moved and held in a 0 index position by the centering lever 99 upon elevation of a depressed key 67 to its initial position, and that the stop pawl 51 of the escapement mechanism is in engagement with a rack tooth 49, insuring appropriate positioning of the cutter blades opposite the corresponding perforations of the first field.

The number 2 key is depressed, which oscillates the selector lever 99, through the key lever inclined cam face 94, and slides the rack bar 72 to rotate the pinion 70 and wheel shaft 68 a predetermined distance, aligning a prong or projection 43a on the number 2 selector wheel 43 with the intermediate, number 2 cutter blade 35. The last depressing movement of the number 2

key closes the circuit for the motor 110 and causes it to rotate and, through the crank 111, connecting rod 113 and leverage mechanism 114, 117, 118, oscillate the levers 69 about the rear guide bar 20, moving the selector shaft 68 upwardly, and causing the number 2 projection 43a to strike the nose 35b on the number 2 blade, shifting its other end 35 downwardly to notch the card. The other punches are not moved because their noses 34b, 36b enter the space between the projections on the other regulator wheels 42, 44. This is also true of all of the regulator wheels 41a on the forward set of the machine, which are locked in a 0 position. The noses on the punches are not engaged by any projections and, consequently, cannot effect a swinging of the punch levers against the action of their return springs 40.

Upon depressing the number 2 key lever, the 20 detent bar 121 engages over the detent nose 120 and prevents its upward return movement. The depressing action of the number 2 key also causes the inner portion of its associated key lever 64 to strike the bar 63 and rock the arm 62 of the escapement mechanism, producing rotation of the shaft 56 to which the stop pawl 57 is secured and lowering of the stop pawl from engagement with the rack teeth 49. This same motion moves the holding pawl 50 in an upward 30 direction, by virtue of the pin and slot connection 53, 54 to engage its nose 52 against a rack tooth 49 and prevent movement of the punch head 19. Following the removal of downward pressure from the number 2 key, it elevates a 35 slight distance under the influence of its return spring 127 to open the motor switch 119 and circuit, the pin 125 on the selector shaft lever 69a engaging the detent lever cam face 124 to move the detent bar 121 forwardly out of engagement with the latch nose 120 on the number 2 key lever, permitting its return spring 127 to re-elevate the lever 64 and remove its cam face 94 from the selector rod 95. The spring 107 and lever arm 103 may now cause the follower 45 roller 106 to shift the selector lever 99 to 0, centered position, which correspondingly shifts the rack bar 72 and selector shaft 68 back to 0 position.

Elevating movement of the key lever 64 permits the spring 62a to raise the lever arm 62 of the escapement mechanism, removing the holding pawl 50 from engagement with the rack tooth 49, and allowing the spring tape 45 to shift the punch head 19 to the right a distance determined by 55 engagement of the next succeeding rack tooth with the stop pawl 57, which has been re-elevated by the spring 62a. Such engagement of the next succeeding rack tooth with the stop pawl 57 positions the punch head 19 and its cutter blades 17 over the next field on the card 10, whereupon the next key, number 5, may be depressed to rotate the selector wheels 41 and position both the number 4 and number 1 prongs 44a, 42a in alignment with the blade fingers 36b, 34b. As before, the 60 depression of the number 5 key completes the circuit to the motor 110 and causes elevation of the selector wheel shaft 68 to actuate the number 1 and number 4 punches 34, 36d and notch the card to the number 1 and number 4 perforations. The 65 other numbers 9, 2 and 1 are also punched by depressing the corresponding keys sequentially, the punching head 19 being shifted progressively in step by step fashion by the spring tape 45 and escapement mechanism to the next succeeding fields, and the card notched appropriately.

The 0 key is not connected with the selector lever 99 at all, its depression merely operating the escapement bar 63 to produce the appropriate movement of the stop and holding pawls 57, 50, causing a shifting of the punching head 19 to the next field without producing any notching whatsoever in the current field. The lack of notching in a field indicates a 0 number.

In the event that it is desired to notch the forward longitudinal margin of the card 10, the side control lever 83 is moved to its bottom position, which will rock the carriage 73 about its pivot 74 through the action of the pin 87 against the curved cam surface 88 on the underside of the rocker carriage, the pin being moved to the other side of the carriage fulcrum 74. Such rocking action engages the forward rack bar teeth 71a with its pinion 70a and removes the latch lever 78a from its engaged position. At the same time, the other latch lever 78 is engaged with its pinion 70 and the rear rack bar teeth 71 disengaged from such pinion. The notching along the lower card edge then can occur in the same manner as along the upper card edge, the depressed keys 67 selecting the register wheels 41a and prongs which are to engage the noses on the cutter blades.

It is, therefore, apparent that a keypunch mechanism has been devised capable of selectively notching both the upper and lower longitudinal marginal edges of a card, in accordance with the depressions of the keys of a single keyboard. A single punching head is positioned progressively adjacent the fields on the selected marginal edge and the same single operating mechanism actuates either the punches for the upper edge of the card or the punches for the lower edge of the card, depending upon the edge to be notched. The entire mechanism embraces a minimum of parts and is simple to construct and operate. Its servomotor actuation permits its operation at a comparatively high speed and with a minimum of effort on the part of the operator, who need merely make the selection of the numbers to be notched and punched in the card through depression of the particular required keys.

While I have shown the preferred form of a machine for practising my invention, I wish it understood that various changes may be made in its construction by those skilled in the art without departing from the spirit of the invention as defined in the appended claims.

Having thus described my invention, what I claim and desire to secure by Letters Patent is:

1. A machine of the character described comprising a frame, means for holding a card on the frame in a predetermined position, guide means extending parallel to the opposed side edges of a card on said holding means, a carriage movable on said guide means and having opposed sets of punches and dies in operative relation to the side edges of a card supported on said holding means, means for actuating said punches including a set of selector members for each set of punches adapted to transmit movement thereto, a single set of key operated means for moving said selector members to determine the punch to be actuated by said actuating means, means for selectively placing said key operated means in operative relation with said sets of selector members in order that only one set of said sets of punches and dies may be effective for operation on a card, and means for automatically shifting said selector members to ineffective position following actuation of a selected punch by said actuating means.

2. A machine of the character described com-

prising a frame, a carriage carried by said frame, sets of punches and dies on said carriage for punching a card on said frame, a set of selector means for each set of punches, common means for moving said sets of selector means to actuate a selected punch, key operated means for indexing said selector means to determine the punch to be actuated by said common means, and means for selectively placing said key operated means in operative relation with said sets of selector means in order that only one set of selector means may be effective for operation on a card, the other set of selector means being held in ineffective relation with respect to its associated set of punches and dies.

3. A machine of the character described comprising a frame, sets of punches and dies for punching a card on said frame, a set of selector means for each set of punches, common means for simultaneously moving said sets of selector means to actuate a selected punch, key operated means for indexing said selector means to determine the punch to be actuated by said common means, and means for selectively placing one of said sets of selector means in operative relation with said key operated means and for holding said other set of selector means from operative relation with said key operating means.

4. A machine of the character described comprising a frame, means for holding a card on the frame in a predetermined position, guide means extending parallel to the opposed side edges of a card on said holding means, a carriage movable on said guide means and having opposed sets of punches and dies in operative relation to the side edges of a card supported on said holding means, a set of selector means for each set of punches, common means for simultaneously moving said sets of selector means to actuate a selected punch, a single set of key operated means for indexing said selector means to determine the punch to be actuated by said common means, means for selectively placing one of said sets of selector means in operative relation with said key operated means and for holding said other set of selector means from operative relation with said key operated means, and means for advancing said carriage step by step along said guide means.

5. A machine for coding a card of the character described comprising fields each having a plurality of numerals or other indicia thereon, said machine comprising a set of punches so disposed as to punch a field in correspondence with said indicia, a rotary selector whose angular position determines the punch or punches to be activated and which is operable to actuate any one or any combination of said punches depending upon its angular position, and key operated means for determining said angular position and for actuating said punches in accordance with said rotary position.

6. A machine for coding a card of the character described comprising fields each having a plurality of numerals or other indicia thereon, said machine comprising a set of punches so disposed as to punch a field in correspondence with said indicia, a rotary member for actuating said punches and so disposed with reference to said punches as to actuate any selected punch or combination of punches depending upon its angular position, means for rotating said rotary member to any selected angular position, means for operatively connecting said rotary member

and said set of punches when said rotary member is in a selected angular position, and key operated means for actuating said rotating means and said connecting means.

7. A machine for coding a card of the character described comprising fields each having a plurality of numerals or other indicia thereon, said machine comprising a set of punch levers so disposed as to punch a field in correspondence with said indicia, means for advancing said set of punches step by step to punch said fields in sequence, a rotary selector member comprising a rotatable shaft having a plurality of similar sets of selector wheels affixed thereto, said shaft being supported for oscillation between a normal, inactive position and an active position wherein said wheels actuate a set of punches, each set of wheels being aligned with a field, each wheel having radial spokes and the spokes of the several wheels of each set being so dis-

posed as to actuate any one or any combination of said punches depending upon the angular position of the shaft, means for rotating said shaft, means for oscillating said shaft, and key operated

means for activating said shaft rotating and shaft oscillating means.
